CLAIM

The ornamental design for a portable water travel mug for dogs, as shown and described.

DESCRIPTION

FIG. 1 is a top-side perspective view of the portable water travel mug for dogs, showing my new design;

FIG. 2 is a bottom perspective view thereof;

FIG. 3 is a front view thereof;

FIG. 4 is a rear view thereof;

FIG. 5 is a left side view thereof; and

FIG. 6 is a right side view thereof;

FIG. 7 is a top view thereof;

FIG. 8 is a bottom view thereof; and,

FIG. 9 is a front view thereon showing the strap in a recessed area.

1 Claim, 9 Drawing Sheets
